Primary Examiner — Dana Meyrow

(74) Attorney, Agent, or Firm — Dawsey Co., LPA;
David J. Dawsey(57) **CLAIM**

The ornamental design for a bottle, as shown and described.

DESCRIPTION

FIG. 1 is a perspective view of a bottle showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The drawings are lined for to represent a copper color. The broken lines show unclaimed subject matter only and form no part of the claimed design.
